UNITED STATES PATENT OFFICE.

JAMES L. MCPHERSON, OF PITTSBURGH, PENNSYLVANIA.

NECKTIE HOLDER AND PRESSER.

1,253,702.

Specification of Letters Patent. Patented Jan. 15, 1918.

Application filed August 1, 1917. Serial No. 183,958.

To all whom it may concern:

Be it known that I, JAMES L. MCPHERSON, a citizen of the United States, residing at Pittsburgh, in the county of Allegheny and State of Pennsylvania, have invented 5 certain new and useful Improvements in Necktie Holders and Pressers, of which the following is a specification.

This invention relates to a necktie holder 10 and pressing device and the object thereof is to provide a simply constructed and efficient device of this character in which a plurality of ties may be held and pressed and from which one or more ties may be 15 removed without interfering with the others contained therein.

Another object is to provide a holder of 20 this character composed of two clamping plates which are adjustable relatively to each other to provide for a variable number 25 of ties being held and pressed between them.

With the foregoing and other objects in view, which will appear as the description proceeds, the invention resides in the combination and arrangement of parts and in the details of construction hereinafter described and claimed, it being understood that changes in the precise embodiment of the 30 invention herein disclosed may be made within the scope of what is claimed without departing from the spirit of the invention.

In the accompanying drawings:

Figure 1 represents a front elevation of 35 this improved device in closed position,

Fig. 2 is a longitudinal section taken on the line 2-2 of Fig. 1,

Fig. 3 is a view in elevation with the plates shown open and parts broken away, and

Fig. 4 is a detail sectional view with the tie holding slotted member shown in down-turned position.

In the embodiment illustrated, the tie holder constituting this invention comprises 45 two clamping plates 1 and 2 hingedly connected at one edge as shown at 3 and which are preferably shaped to conform to the ends of the ties to be held and pressed thereby. These plates 1 and 2 may be composed of any suitable material and decorated on their outer faces in any suitable or desired manner. The inner faces of these plates are lined with felt, cloth or other suitable fabric which will prevent injury to ties 55 clamped between them.

Connected with the upper edge of plate 2 and hinged thereto as shown at 4 is a transversely slotted plate 5 thereby forming a plurality of cross strips 6 spaced apart a sufficient distance to permit the insertion between them of the folded portion of the tie to be pressed as will be hereinafter more fully described. This slotted plate 5 is provided at its hinged end on opposite sides 60 with projections or lugs 7 which are designed to engage plate 2 for limiting the downward swinging movement of said plate 5.

Apertured ears 8 project laterally from the opposite side edges of plate 2 at its 65 upper end and are designed as attaching means for connecting the device to a wall or other suitable support. The free side edges of plates 1 and 2 are provided, one with a spring tongue 9 and the other with a slotted 70 latch member 10 through which the spring tongue 9 is designed to project and to engage. By providing a plurality of these slots in this member 10 the device is designed to accommodate a variable number 75 of ties and to so clamp them that they will be pressed and the creases made therein by wearing removed.

In the use of this device, the small ends of the ties to be held and pressed thereby 80 are first drawn through the slots formed between the cross bars 6 of plate 5 and then folded intermediately of their ends and said small ends passed over the cross-bars and down through an adjacent slot, it being 85 understood that one tie is passed through each slot and the free ends of the ties lie between the plates 1 and 2 which latter are made sufficiently large to entirely encompass said ends. After the ties are so positioned, 90 the plates 1 and 2 are folded together and secured by means of the spring tongue 9 being passed through one of the slots in the latch member 10. By clamping these two plates tightly together it will be obvious 95 that the ties between them will be pressed and all wrinkles removed so that when it is desired to use a tie, the plates may be opened by disengaging the members 9 and 10 and removing one of the ties without in any way 100 interfering with those remaining.

It is to be understood that when the ties have been inserted and are in operative position within the holder, the plate 5 will drop down into a plane at right angles to plates 105

1 and 2 and the lugs 7 engaging the upper end of the plates will operate to limit the downward movement of plate 5.

From the above description it will be obvious that as many ties may be clamped between the plates 1 and 2 as there are slots in plate 5 and in the form here shown, six slots are used. If however, these slots are made far enough apart, two ties might be inserted in one of them and the means for securing the plates in clamped position, being adjustable, will permit quite a number to be held between them.

I claim:—

15. 1. A tie holder of the class described comprising a pair of clamping members, means for connecting said members in closed position, and a hinged tie receiving member carried by one end of said members, and opening in a direction at right angles to that in which said members open.
20. 2. A tie holder of the class described comprising a pair of clamping members, means for connecting said members in closed position, and a hinged tie receiving member carried by one end of said members, said member being provided with a plurality of transversely extending slots through which

the folded intermediate portion of the ties are designed to pass.

3. In a device of the class described, a pair of plates hingedly connected at one edge, means for adjustably connecting their opposed edges, a hinged plate carried by the upper edge of one of said plates, said hinged plate being provided with a plurality of transversely extending slots, and means for limiting the downward movement of said plate.

4. A device of the class described comprising a pair of clamping plates tapering toward one end and hingedly connected at one edge, means for adjustably connecting their free edges, a plate hinged to the smaller end of one of said clamping plates and having laterally extending stop lugs for limiting its downward swinging movement, said hinged plate being provided with a plurality of longitudinally spaced transversely extending slots.

In testimony whereof I affix my signature in presence of two witnesses.

JAMES L. McPHERSON.
